Primary Examiner — Charles D Hanson

(57) **CLAIM**

The ornamental design for a storage box for screwdriver bits, as shown and described.

DESCRIPTION

FIG. 1 is a front elevation view of a storage box for screwdriver bits showing the new design;
FIG. 2 is a back elevation view thereof;
FIG. 3 is a left-side view thereof;
FIG. 4 is a right-side view thereof;
FIG. 5 is a top plan view thereof;
FIG. 6 is a bottom plan view thereof;
FIG. 7 is a perspective view thereof;
FIG. 8 is another perspective view thereof; and,
FIG. 9 is a perspective view of the storage box for screwdriver bits in an open position.
The broken lines depict portions of the storage box for screwdriver bits that form no part of the claimed design.

1 Claim, 9 Drawing Sheets
